FOREIGN PATENT DOCUMENTS

JP 2005242409 A * 9/2005

Primary Examiner — Patricia A Palasik(74) *Attorney, Agent, or Firm* — Polsinelli PC(57) **CLAIM**

I claim the ornamental design for a modular robot with backpack assembly, as shown and described.

DESCRIPTION

FIG. 1 is a perspective view of a modular robot with backpack assembly, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Broken lines are for illustrating unclaimed portions of the modular robot with backpack assembly; the broken lines form no part of the claimed design.

1 Claim, 7 Drawing Sheets(56)
